UNITED STATES PATENT OFFICE.

WILLIAM F. GREEN AND LAUD C. GATES, OF MODESTO, CALIFORNIA; SAID GATES
ASSIGNOR TO SAID GREEN.

RADIATOR WATER-GAGE.

1,373,129.

Specification of Letters Patent. Patented Mar. 29, 1921.

Application filed March 3, 1919. Serial No. 280,415.

To all whom it may concern:

Be it known that we, WILLIAM F. GREEN and LAUD C. GATES, citizens of the United States, residing at Modesto, county of Stanislaus, in the State of California, have invented certain new and useful Improvements in Radiator Water-Gages, of which the following is a specification.

This invention is a gage particularly useful for gaging the amount of water in an automobile radiator.

The object of the invention is to provide an adjustable water gage for automobile radiators, and like usages, which may be applied to any size and style of radiator and at the same time provides a strong and rigid construction which is durable and efficient.

The invention resides in the sundry details of construction, combination and arrangement of parts hereinafter set forth.

The invention is illustrated in the accompanying drawings which form a part of this specification and the appended claims.

Referring to the drawing:

Figure 1 is a front elevation of the gage. Fig. 2 is a side elevation of the gage.

Fig. 3 is a cross section of the gage on line 3—3 of Fig. 2.

Fig. 4 is a front elevation of an automobile radiator and the gage applied thereto.

In the drawings, 1 indicates a glass tube inclosed by a tubular metal casing 2 provided with a longitudinal slot 3. The lower end of said casing and tube are mounted in a bracket 4 while the upper portion of said casing and tube are mounted in a bracket 5. A cap 6 closes the upper end of the tube 1 and casing 2, but is provided with a small air vent to permit escape of the air which becomes trapped in the tube. A nipple 7 is connected to the lower end of tube 1. A threaded rod 8 screws through the bracket 4 and a bracket 9 is secured to the lower end of said rod in which is screwed a fitting 10 formed with a nipple 11 on its upper end and with a nipple 12 and a drain conduit 13 on its lower end, a drain cock 14 being screwed into the lower end of said drain conduit.

The brackets 4, 5 and 9 are provided with screw openings 15 through which screws 16 are inserted and screwed into the front of an automobile radiator 20 to support the gage on the radiator, the bracket 9 being adjustable with relation to the bracket 4 to fit

radiators of different sizes. A flexible tube 21 fits at its ends on nipples 7 and 11 and connects the tube 1 with the fitting 10. A tube 22, preferably of copper or lead is fitted at one end on nipple 12 and at its other end on the nipple of a cock 23 leading from the bottom of the automobile radiator through which cock and the tube 22, fitting 10, tube 21 and nipple 7, water from the radiator is admitted into the gage tube 1 until it reaches the level of the water in the radiator. A red ball 25 floats on top of the water in the tube 1 for indicating the level of the water in the radiator, said ball being visible through the slot 3 of tube 2 and the glass tube 1.

It will be seen that the construction as above set forth provides a gage which may be adjusted to fit any size of radiator and to extend the full length of the radiator. The parts of the gage are rigidly connected together to prevent rattling and wear which is caused by loose parts and connections. The flexible tube 21 may be provided of such length as will be necessary for the largest type of radiator, and the purchaser will only be required to cut the tube to the desired length after he has properly adjusted the gage for the size of radiator on which it is to be used.

The foregoing fully describes the invention, however, it is to be understood that certain changes may be made in the construction, combination and arrangement of parts which fall within the legitimate scope of the appended claims.

Having described our invention, we claim as new:

1. An adjustable radiator gage comprising a pair of bracket members rigidly and adjustably connected together, one of said brackets having a gage tube secured thereto and the other of said brackets carrying a connection-fitting adapted to be connected to the lower portion of a radiator or tank, and a flexible connection between said fitting and gage tube.

2. An adjustable gage for automobile radiators comprising a pair of bracket members engageable with the front of the radiator and adjustably and rigidly connected together by a rod, one of said brackets having a gage tube secured thereto and the other of said brackets carrying a connection-fitting adapted to be connected to the lower

portion of the radiator, and a flexible connection between said fitting and gage tube.

3. An adjustable gage tube for automobile radiators, comprising a pair of superposed brackets, a threaded rod adjustably connecting said brackets together, a gage tube secured to the upper bracket and extending upwardly therefrom, a connection-fitting secured to the lower bracket and adapted for

connection with the lower portion of the 10 radiator, pipe sections extending from opposing faces of the brackets, and a flexible connection between said pipe sections.

In testimony whereof we affix our signatures.

WILLIAM F. GREEN.
LAUD C. GATES.
